UNITED STATES PATENT OFFICE.

LOUIS WOLFSKY, OF CHICAGO, ILLINOIS.

DESIGN FOR A PICTURE-FRAME BRACKET.

SPECIFICATION forming part of Design No. 21,452, dated April 5, 1892.

Application filed December 23, 1891. Serial No. 416,006. Term of patent 7 years.

To all whom it may concern:

Be it known that I, LOUIS WOLFSKY, a citizen of the United States, residing at Chicago, in the county of Cook and State of Illinois, have invented a certain new and original 5 Design for Picture-Frame Brackets, of which the following is a full, clear, concise, and exact description, reference being had to the accompanying drawing, forming a part of this specification.

The drawing is a front view in perspective of a picture-frame bracket, showing my design, and is deemed adequate to fully illustrate my invention.

15 The leading feature of my design consists in a bracket attached to the lower part of the picture-frame, said bracket conforming in configuration to a sofa with arms at each end. The bracket is substantially of the same length 20 as the picture-frame and serves as the base of said frame.

In the drawing the frame A A A is shown with three sides of ornamented picture-frame molding. The lower side B forms a bracket in the shape of a sofa with the scroll-like arms 25 C C at each end. I also place an ornamental molding D along the base of the bracket. The space within the frame E E may be divided into panels, as shown, for the reception of mirrors or pictures. 30

What I claim is—

The design for a picture-frame bracket, herein shown and described.

In witness whereof I hereunto subscribe my name this 16th day of December, A. D. 35 1891.

LOUIS WOLFSKY.
